UNITED STATES PATENT OFFICE.

BRADFORD D. COFFEY, OF JERSEY CITY, NEW JERSEY.

ELECTRICAL COMPOUND LETTER.

Application filed August 17, 1925. Serial No. 50,771.

This invention relates to electrical signs and particularly to an improved sign wherein all the letters of the alphabet, numbers and other configurations may be produced by causing different groups of lights to be lighted.

The object of the invention is to provide a sign wherein different letters or other configurations may be made from the same set 10 of lights by lighting different groups of lamps at different times.

Another object of the invention is to provide an electric sign wherein is utilized a large number of lamps, the lamps being arbitrarily located so that by switching on certain groups different letters or other configurations may be produced and most of the lamps used at different times in forming certain groups.

A further object of the invention is to provide 20 an electric sign composed of electric lamps arranged in arbitrary groupings and associated with a source of power, suitable wiring and a switch mechanism including a single movable member for substantially instantaneously lighting a different group of lamps so as to provide a different letter or other configuration.

An additional object of the invention is to provide 30 an electric signal wherein groups of lamps are provided and associated with certain switch mechanism whereby upon the proper actuation of the switch mechanism successive letters may be formed whereby any desired number of words may be spelled out 35 in succession so as to present as long a message as desired.

In the accompanying drawings—

Figure 1 is a diagram of a letter disclosing 40 an embodiment of the invention, the same being provided with dot and dash lines indicating the outline of the various letters when formed.

Figure 2 is a diagram of the letter A.

Figure 3 is a diagram of the letter C.

Referring to the accompanying drawings by numerals, 1 indicates a series of dotted lines along which the various lamps 2 are arranged. It will be noted that these lamps are not arranged in rows but are arbitrarily positioned on the various lines 1 whereby any

letter of the alphabet and certain other configurations may be secured by turning on current to the various electric lamps 2 according to the group desired.

In forming the letters A and C as shown in 55 Figures 2 and 3, a large number of the same lamps are used but certain lamps are added in the letter C and certain lamps are not used in the letter C. It is to be noted that the lamps 2 are electrical lamps of any desired 60 kind and that they may have a common return arranged in any desired manner.

In the drawing, only one compound letter is shown but it will be understood that any desired number of these letters may be arranged in a horizontal row or in a vertical row or in fact, in any other desired way. Where there are several superimposed horizontal rows, an operator may readily spell out one or more words and leave the same 70 burning or may open the circuit of the various lamps and spell out another set of words. As clearing indicated in Figure 1, the various lamp members 2 are arranged on the dot and dash lines 1 and these lines present horizontal rows of lamp members 3, vertical rows of lamp members 4, together with a V-shaped arrangement 5. Also, diagonal rows 6 are arranged at the corners and substantially V-shaped rows 7 arranged in the center, together 75 with inclined rows 8 and 9 whereby a composite letter is provided which will present lamp members so arranged as to use a straight line effect in forming any letter or number.

What I claim is:

85 A compound letter for electric signs comprising a plurality of series of lamp members, each series being arranged in a straight line, said series of lamp members including a plurality of vertical rows of lamp members, a 90 horizontal row of lamp members at the top and bottom, a horizontal row at the center, a pair of diagonal rows of lamp members, one of said diagonal rows extending from one corner to the opposite corner at the opposite end 95 and the other diagonal row of lamp members connecting the remaining corners, said diagonal rows of lamp members converging at the center of the letter, a straight row of lamp members adjacent each corner of the 100

letter positioned diagonally across the respective corners, a pair of rows of lamp members forming a V extending from the two upper corners to the central lamp member at the lower end of the letter, a pair of V-shaped rows of lamp members at the center with their apexes extending at right angles to the

vertical, and an inclined row of lamp members extending from one of the upper corners of the letter at an angle downwardly to the opposite side of the letter and passing through a lamp member half-way between said opposite side and the center of the letter.

BRADFORD D. COFFEY.
